(57) **CLAIM**

The ornamental design for a garment, as shown and described.

DESCRIPTION

FIG. 1 is a front perspective view of a garment that is in an in-use configuration showing the present design;

FIG. 2 is a front view thereof;

FIG. 3 is a back view thereof;

FIG. 4 is a first side view thereof; and,

FIG. 5 is a second side view thereof.

The evenly spaced broken lines shown in the drawings are directed to environment, are for informational purposes only, and form no part of the claimed design.

The long and short broken lines are boundary lines, which define bounds of the claimed design. These boundaries do not exist in reality in the article embodying the design. It is understood that the claimed design extends to these boundaries but does not include the boundaries.

1 Claim, 5 Drawing Sheets
